CLAIM

The ornamental design for a vehicle wheel, as shown and described.

DESCRIPTION

FIG. 1 is front view of a vehicle wheel, showing my new design;

FIG. 2 is a perspective view thereof;

FIG. 3 is a front view of a second embodiment of a vehicle wheel, showing my new design;

FIG. 4 is a perspective view of FIG. 3;

FIG. 5 is a front view of a third embodiment of a vehicle wheel, showing my new design; and,

FIG. 6 is a perspective view of FIG. 5.

The broken lines showing of environment in FIGS. 1-6 is for illustrative purposes only and forms no part of the claimed design.
